UNITED STATES PATENT OFFICE.

FRANCIS L. DAVIS, OF BOTHELL, WASHINGTON, ASSIGNOR OF ONE-HALF TO JOSEPH C. CURTIS, OF KING COUNTY, WASHINGTON.

DESIGN FOR A BOOK COVER.

Application filed August 26, 1927. Serial No. 23,216. Term of patent 3½ years.

To all whom it may concern:

Be it known that I, FRANCIS L. DAVIS, a citizen of the United States, and a resident of Bothell, in the county of King and the State of Washington, have invented a new, original, and ornamental Design for Book Covers, of which the following is a specification, reference being had to the accompanying drawing, forming a part thereof.

In the drawing the figure is a face view of a book cover showing my new design.

I claim:

The ornamental design for a book cover as shown.

FRANCIS L. DAVIS.
